UNITED STATES PATENT OFFICE.

JOHN JANN, OF NEW WINDSOR, MARYLAND.

IMPROVEMENT IN HARVESTERS.

Specification forming part of Letters Patent No. 55,304, dated June 5, 1866.

To all whom it may concern:

Be it known that I, JOHN JANN, of New Windsor, in the county of Carroll and State of Maryland, have invented certain new and useful Improvements in Harvesters; and I do hereby declare the following to be a full, clear, and exact description of the nature, construction, and operation of the same, reference being had to the accompanying drawings, which are made part of this specification, and in which—

Figure 1 is a plan of a harvester illustrating my invention. Fig. 2 is a rear-end elevation of the same. Fig. 3 is a side elevation with the right wheel removed.

Similar letters of reference indicate corresponding parts in the two figures.

My said invention consists, first, in novel means for throwing the cutting apparatus out of gear with the axle by which it is driven; second, in a peculiar device for attaching the cutter-bar to the main frame; third, in the arrangement of devices for raising and lowering the cutting apparatus; fourth, in a device whereby the cutter-bar may be stiffened so as to be adapted to be raised at both ends in passing over obstructions or in being elevated when the operation is to be suspended.

The following description in connection with the drawings will enable others skilled in the art to which my invention appertains to fully understand and use the same.

A represents the main frame, and B the cutter-bar. The axle C is intended to drive the cutter-bar through gearing inclosed within the main frame. On the hub of each driving-wheel D is a ratchet, D', which, for the sake of economy and simplicity of construction, I cast in one piece with the wheel.

E E are movable ratchets or clutches fitted to slide upon the axle C, and employed in connection with the respective ratchets D' D' for the purpose of causing the axle C to turn with the wheels D or permit the latter to turn loosely, thereon without rotating the axle, as occasion may require.

F F may represent semi-cylindrical or other suitably-shaped slides, each of which is formed with a flange, f, Fig. 2, which fits within the groove e of the clutch E. Each slide F is guided in its movement by the projection G, and is confined upon the sleeve C' of the axle g.

H is a lever fulcrumed upon the main frame at h, and having two downwardly-projecting

pins, h' h', one at each side of the fulcrum. These pins h' fit into proper recesses or holes in the outer edges of the sliding bars I I, and under the lateral impulse of the lever are adapted to move the bars I in an outward direction, so as to couple or engage the clutches E with the ratchets D'.

The slide F and clutch E are connected as above described, so as to move together, and the slides are connected to the bars I by means of the bars J. In the adjacent faces of the bars I I are recesses i i, which are in opposition or in line with each other at the same time that the clutches E are engaged with the clutches D'. By introducing a key or pin into the recesses i i the parts may be held in gear permanently, or at least until the wedge or key is removed; but when the latter is withdrawn from the recesses in the bars I I said bars are acted upon by the springs K K, which have a tendency to hold the parts out of gear by pressing against the ends of the bars, as shown. The springs K are bolted or otherwise attached to the main frame.

O is a bar, slotted longitudinally at o, and fastened to the finger-beam by means of the screw-bolt P. This bar is adapted to be slid inward till its end projects under the pivot-bolt M, which attaches the finger-beam to the double shear bar N. When the end of the bar O is thus projected inward beneath the pivot-bolt M a stiff joint is made between the cutting apparatus and the double shear bar to which it is connected, so that on raising the said double shear bar the outer as well as the inner side of the cutting apparatus will be elevated either to pass over obstructions or suspend the operation. The bar N is connected by a hook, Q, and link R to a cogged segment, S, which is pivoted to the main frame at s.

T is a lever which is attached to and rotates a stud-shaft, which carries a pinion, U, which meshes with the cogs of the segment S.

The link R has a slot, r, extending through it in the direction of its length, and through this slot passes the pin s', which attaches the link to the segment S. Hence the link which sustains the cutting apparatus allows the latter to rise and fall freely in order to conform to undulations of the earth. The lever T is employed for elevating and lowering the cutting apparatus.

By drawing the end of the bar O from under

the pivot-bolt M a loose or flexible joint will be made between the cutting apparatus and the double shear bar N.

Having thus described my invention, the following is what I claim as new and desire to secure by Letters Patent:

1. The arrangement of the lever H, bars I, slides F, clutches E, ratchets D, and springs K, as and for the purposes specified.

2. The slotted bar O, in combination with the pivot-bolt M, for making a stiff joint between the cutting apparatus and its connections.

3. The combination of the double bar N, hook Q, slotted link R, segment S, pinion U, and lever T, all arranged and operating as described.

To the above specification of my improvements in harvesters I have signed my hand this 23d day of September, 1865.

JOHN JANN.
